COMBINED ADJUSTABLE HORIZONTAL BAR AND INCLINE TABLE FOR EXERCISING

Edgar F. Ryan, Beachwood, Ohio
(653 Broadway, Bedford, Ohio)

Filed Mar. 30, 1960, Ser. No. 59,960

Term of patent 14 years

(Cl. D83—1)

The figure is a top perspective view taken from the front and left side of a combined adjustable horizontal bar and incline table for exercising embodying my new design, the right side not shown being substantially the same as the left side shown.

I claim:

The ornamental design for a combined adjustable horizontal bar and incline table for exercising, substantially as shown and described.
